[57] ABSTRACT

A control system for a compacting machine is provided which includes a compaction chamber into which material to be compacted is placed, a pressure plate spanning the area of the chamber for compressing the material, and a reversible drive source for moving the pressure plate in forward and reverse directions within the chamber. The control system selectively enables driving of the pressure plate to effect performance of baling, packing and return cycles of the machine and provides output indications of the operating condition of the machine, the direction of movement of the pressure plate, and the full condition of the compaction chamber. A time delay circuit automatically shuts down the machine when any of the operational cycles continues beyond a predetermined time limit.

CONTROL SYSTEM FOR A COMPACTING MACHINE

DESCRIPTION OF THE INVENTION

The present invention relates generally to electrical control systems and more particularly concerns the electronic control of a power-assisted compaction machine.

Compaction machines have become increasingly popular for reducing the volume of paper waste and other useful but bulky commodities, as well as for the crushing of refuse in both home and commercial environments. The rapidly expanding usage of such machines has compounded the incidence of injury resulting from the inherent dangers attendant to the operation of the power-assisted compaction process. Conventional compaction machines have employed few, if any, safety features beyond the usual safety interlock on the door to the compaction chamber.

It is a general object of the present invention to provide a control for a compacting machine which provides a degree of safety to the operator which has heretofore been unavailable in such machines. More specifically, it is an object of the present invention to provide a control system for a compaction machine which includes a non-defeatable door interlock and which provides for the operator visual indications of the operating condition of the machine so as to minimize the possibility of injury resulting from operator mistake in using the machine.

It is a more specific object of the present invention to provide a control system for a compacting machine which gives visual indications of the operating or "ON" condition of the machine, the direction of movement of the pressure plate and the full condition of the compaction chamber.

Yet another object of the present invention is to provide a control system which protects the operator and the machine in the event of a malfunction which causes any operational cycle of the machine to continue for an excessively long time period. A related object of the invention is to provide for automatically shutting down the machine when any of the operational cycles continues beyond a normal time period.

Prior compaction machines have also been devised for operation in a baling mode, in which the contents of the compaction chamber are held in a compressed state for manual binding by the operator. However, the known machines useful for this purpose have required that the operator continually monitor the operation of the pressure plate and manually shut down the machine at or near the point of maximum compaction pressure.

Therefore, it is another object of the present invention to provide a compaction control system having an automatic baling capability which frees the operator from constant surveillance of the pressure plate position and pressure. Most specifically, it is an object to provide a control system which senses the condition of maximum compaction pressure during the baling operation and automatically holds the compaction chamber contents in a compressed maximum-pressure state so as to facilitate baling.

A still further object of the present invention is the provision of a control system which provides repetitive tamping of the chamber contents during each operational cycle of the machine as the chamber volume

reaches the full level, thus creating a tightly compacted bundle. Other objects and advantages of the present invention will become apparent upon reading the following detailed description and upon reference to the drawings, in which:

FIG. 1 is an elevational view of a compaction machine embodying a control system constructed in accordance with the present invention;

FIGS. 2a-2c, when taken together, constitute a schematic diagram of the electrical circuit used in the control system of the present invention.

FIGS. 3a-3b are exploded detail views of a limit switch arrangement.

While the invention will be described in connection with preferred embodiment, it will be understood that I do not intend to limit the invention to that embodiment. On the contrary, I intend to cover all alternatives, modifications and equivalents as may be included within the spirit and scope of the invention as defined by the appended claims.

Turning now to FIG. 1, there is shown a compaction machine having an exterior housing 10 divided into a compaction compartment 12 and a control compartment 14. A hinged door 16 provides general access to the compaction chamber 12 and includes a handle and lock mechanism 18 of conventional type. A box 20 is placed in the lower section of the compaction compartment 12 for receiving the material to be compacted, removal of the box 20 being facilitated by an ejection strap 22 which generally lies behind and under (from the operator's standpoint) the box 20. At the lower end of the ejection strap 22 is a handle 24 through which the operator's hand may be inserted during ejection of the box 20. At a point above the level of the box 20 there is provided in the door 16 an aperture 26 normally covered by a hinged door 28 which, when opened, forms a chute through the door 16 into the box 20.

During normal service as a compacting machine, the material to be compacted is inserted into the closed chamber 12 through the chute formed in the aperture 26 of the door 16. For compressing the contents of the chamber 12 a pressure plate 30 is provided which of such a size as to substantially span the horizontal area of the chamber 12 and, in particular, the horizontal area of the box 20. The plate 30 is guided by a pair of vertically extending guide bars 32, 34 extending upward into the control chamber 14.

For moving the pressure plate 30 in the forward and reverse directions through the compaction chamber 12, there is provided a reversible drive source in the form of a motor and hydraulic pump, indicated generally at 40, which positions a hydraulic ram 42 which runs downward through the machine into engagement at its lower end with the pressure plate 30. A reservoir 46 provides hydraulic fluid for the motor 40.

Although many different drive sources could be employed with the present invention, a particularly suitable drive source, and the one envisioned in the following description, includes a two-stage double pump having a solenoid-controlled directional valve which is actuatable to change the direction of motor force on the hydraulic ram 42. The pump is driven by an electrical motor selectively controlled by an electrical relay in a manner hereinafter described. Also housed in the chamber 14 is a control circuit module 50 having a

front panel housing a plurality of indicators and switches hereinafter described.

Turning now to the control circuit shown in FIGS. 2a-2c, it is seen that electrical line power is provided through a three-prong grounded plug 60 from a conventional 120 volt a.c. supply circuit. The two "hot" sides of the power line have switches 62, 64 connected in series therewith and controlled manually by a front panel key-locked actuator 66. The motor 68 of the hydraulic motor and pump unit 40 is selectively connected across the switched side of the 120 volt line by a normally opened contact set 70 of the drive motor relay 72. Similarly, a drive solenoid 74 for the directional valve of the motor and pump unit 40 is connected in series across the switched 120 volt line through a pair of normally opened contacts 76 of the directional hydraulic valve relay 78.

For converting the a.c. electrical input power into a plurality of d.c. electrical voltages for use in the control circuit, there is provided a power supply module, indicated generally at 80, including a principal supply transformer 82 having a primary winding 84 one half of which is connected in series with the switched supply lines through a protection fuse 86. A neon lamp 88 in series with a current-limiting resistor 89 is also connected across the same half of the primary winding 84 to provide a visual indication of the presence of 120 volt a.c. input voltage to the power supply module 80, and is located on the power supply module 80. A secondary winding 90 of the split type is center tapped to provide a ground line 92 and, operating in conjunction with a pair of rectifier diodes 94, 96 forms part of a conventional full-wave rectifier commonly used in the power supply art. The output from the rectifier is applied across a smoothing capacitor 98 which, to a large degree, removes the ripple from the rectified signal and provides a first d.c. voltage on a supply output line 110 which is applied to one side of both the motor drive relay 72 and the directional hydraulic valve relay 78. The output line 110 also provides power for the pressure plate direction indicator lights 246, 300 and the full condition lamp 440 in a manner hereinafter described.

A second and lower d.c. supply voltage is provided on an output line 114, which is connected to the power line 110 through a dropping resistor 116 and is further regulated by a smoothing network consisting of a capacitor 118 and resistors 119, 120. The d.c. supply line 114 provides a low level d.c. signal, typically 12 volts, for the small-signal switching circuits hereinafter described.

In accordance with one aspect of the present invention, an output indication is provided whenever the main key-operated power switch 66 is actuated. To this end, a third output from the power supply module 80 is provided on an output line 122, which is connected to the output line 114 through a dropping resistor 124. An indicator light 126 is provided on the front panel of the module 50 and is connected to the output 122. Sufficient current is drawn through the dropping resistor 124 to actuate the light 126 to a low but visible level of illumination indicating that the operating switch 66 is on but that at least one of the doors 16, 28 to the cabinet is not closed.

A related feature of the invention lies in the provision of a magnetic interlock switch which cannot be defeated by normal techniques and which deprives the

control circuit of the d.c. operating power whenever the doors 16, 28 to the cabinet are open. To this end, a magnetically actuated switch 130 is provided in series with the d.c. supply output 114 and the operate lamp 126, the series circuit further including an operating diode 132 between the magnetic switch 130 and the lamp 126. A permanent magnet 134 is installed in the chute door 28 (FIG. 1) and is operative to close the contact of the switch 130 whenever the doors 16, 28 are both closed at the same time so as to bring the magnet 134 into proximity with a detecting pickup 136 located on the side panel 10. An indication of the closed condition of the two doors 16, 28 is provided by the lamp 126, which is illuminated to a high brilliance by current flowing through the magnetic switch 130 and diode 132 from the d.c. supply line 114.

The control system of the present invention can be broadly characterized in terms of its principal modes of operation, which are briefly set forth here and described in detail in a later section of the specification.

First, one of the principal modes of operation is the compaction or PACK function, in which the pressure plate 30 moves from its uppermost or RETURN position down through the chamber 12 to compact the material previously inserted therein, followed by the automatic return of the pressure plate 30 to its uppermost position. To this end, the control system provides means responsive to a packing initiation signal and operatively associated with the reversible drive source to cause advancement of the pressure plate 30 in the downward direction to compress the contents of the chamber 12. Pressure sensing means associated with the drive source produces an output signal when the compression pressure on the contents of the chamber 12 has reached a predetermined threshold level, and additional means respond to this output signal from the sensing means to reverse the direction of operation of the drive source so as to retract the pressure plate 30. Finally, position responsive means renders the drive source inoperative on the achievement of the fully retracted position of the pressure plate 30.

It is usually unnecessary for the top panel 11 of the compaction chamber 12 to be resistant to the compaction pressure normally attained in the chamber 12 inasmuch as these pressures are exerted downwardly on the side walls and bottom of the chamber by the pressure plate 30. For this reason the top panel 11 of the compaction chamber is usually formed of relatively light-weight material and is not adapted to withstand high pressures. Under these circumstances it is possible, however, that some refuse being compressed may inadvertently bypass the pressure plate 30 during downward travel of the plate in the chamber, with the result that some such material ends up on top of the pressure plate. Another way in which this could occur would be if the operator inadvertently admitted refuse to be compacted into the chamber 12 when the pressure plate 30 was in some position other than its uppermost position.

For the purpose of detecting the presence of any refuse being compacted on top of the pressure plate 30 soon enough to prevent damage to the top panel 11 of the chamber 12, a limit switch arrangement 31 is provided, as shown in FIGS. 3a and 3b. The limit switch arrangement 31 includes a vertically disposed rod 33 which is slidably mounted to the frame 35 of the com-

paction machine by means of a pair of vertically spaced pillow blocks 37 and 39. The lower end of the rod 33 is arranged to extend downwardly slightly into the compaction chamber 12 when the pressure plate 30 is not in its uppermost position (see FIG. 3b). when the pressure plate moves upwardly in the chamber 12 toward its uppermost position, it approaches and engages the lower end of the rod 33 and accordingly forces the rod upwardly. Means in the form of a collar 41 provided near the upper end of the rod 33 is provided for terminating upward movement of the pressure plate 30 when the plate is in its uppermost position by tripping the switch 164 also mounted on the frame 35 of the machine (see also FIG. 1). A keeper collar 43 is also provided on the rod 33 to hold the rod in place during repair if necessary, and other collar 45 mounted near the lower end of the rod 33 limits the downward movement of the rod into the compression chamber 12 by engagement with the top panel 11. The rod 33 is biased by means of a coil spring 47 disposed between the upper pillow block 37 and the switch actuating collar 41, the spring normally urging the rod downwardly so that the lower collar 45 is disposed against the top panel 11 of the compaction chamber 12.

Thus it is seen that the pressure plate 30 moves upwardly within the chamber 12, if any refuse is inadvertently present in the space between the pressure plate and the top panel 11 of the compaction chamber, the limit switch arrangement 31 will function to terminate upward movement of the pressure plate (via the collar 41 and switch 164) before compaction of the refuse can result in damage to the top panel 11.

Second, the control mechanism provides a tamping or TAMP function when the volume of the compaction chamber 12 approaches a predetermined full level. If a second compaction immediately following the first compaction brings the volume of the chamber 12 below the full level, additional material may be inserted. If, however, after the second compaction the volume remains above the full level, the operator is signaled with a visual indicating light that the chamber 12 is full, indicating that the contents should be removed before further compacting is attempted. To this end, the apparatus described above further includes a volume sensing device providing an indication that the compressed volume is less than a predetermined threshold volume and a time delay device associated with the aforementioned pressure and volume sensing devices and operative to begin a timed period whenever the output signal from the pressure sensing device occurs before the compressed volume falls below the predetermined threshold volume. Finally, there is provided means responsive to the end of the timed interval to reverse the direction of the drive source so as to cause a second compression of the contents of the chamber 12. After this occurs additional means are provided for illuminating the full condition indicator lamp 440 if, a second compression having occurred, the output signal from the pressure sensing means again occurs before the compressed volume has fallen below the predetermined threshold volume.

Third, the control system of the present invention provides an automatic baling function. In the BALE mode, the pressure plate 30 responds to a baling initiation signal to advance through the chamber 12 until the pressure of the contents of the chamber 12 against the pressure plate 30 reaches a predetermined threshold

value. The output signal generated in response to this maximum pressure condition acts upon means associated with the drive source to stop the forward advancement of the pressure plate 30 and hold the contents of the chamber 12 at the predetermined threshold pressure. Finally, means are provided for reversing the operation of the drive source in response to a manual initiation by the operator so as to retract the pressure plate 30 and allow removal of the compressed contents.

10

Various other features of the present invention, such as the automatic shut-off safety feature, will become apparent from the following detailed description of the circuits of FIGS. 2a-2c.

15 Returning then to FIG. 2a, there is shown a manual mode selector switch 140 of the momentary contact type with contacts 142 through 146 and spring biased to a central OFF position. The contact 141 is electrically connected directly to the output line 114 from the d.c. supply 80, while the contacts 143, 145 are connected to the same output line 114 through the magnetic door interlock switch 130. The switch 140 is a three-position switch having, in addition to the OFF position, BALE and PACK-RETURN positions. Three 20 principal output terminals 148, 150, 152 are controlled by the switch 140 and provide the primary function initiating signals for the control system. Specifically, during normal operation the terminal 148 is high (a positive d.c. voltage) whenever the mode selector switch 140 is in the OFF or BALE positions and low whenever the switch 140 is in the PACK-RETURN position. That is, the contacts 141, 142 are normally closed whenever switch 140 is in the OFF or BALE position and normally open whenever switch 140 is in the PACK- 25 RETURN position. The terminals 150, 152 are supplied by the d.c. supply output line 114 when the mode selector switch 140 is respectively in the BALE and PACK-RETURN positions, assuming that the doors 16, 30 28, and hence the magnetic switch 130, are closed. That is, the contacts 143 through 146 are normally open. The contacts 143, 144 are closed only when the switch 140 is in the BALE position and the contacts 145, 146 are closed only when the switch 140 is in the PACK-RETURN position. At all other times, the terminals 150, 152 are electrically isolated. As such, the switch 140 may be manually engaged to provide a packing initiation signal on the terminal 152 or a baling initiation signal on the terminal 150.

35 For the purpose of sensing when the resistance pressure of the contents of the chamber 12 against the pressure plate 30 reaches a predetermined threshold value, there is provided a pressure sensing switch 160 of the single-pole double-throw type having its common pole connected to the interlocked output of the power supply 80 through a dropping resistor 162 and a normally-closed switch 164. The details of the pressure switch 160 are within the knowledge of those skilled in the art and need not be set forth here. Suffice it to say that the contact arm of the switch 160 normally assumes the lower (shown) position when the pressure is below threshold and is actuated to the upper position when the pressure is above threshold. The switch 160 may be responsive to mechanical stress on the pressure plate 30 or chamber 12 for instance. Preferably, however, the switch 160 is hydraulically actuated and is responsive to the build-up of pressure fluid behind the hydraulic ram 42. In its lower position, the switch 160 nor-

mally provides a positive supply signal to a terminal 166 which controls driving down of the pressure plate 30, subject, of course, to the various switching activities upstream of the switch 160.

The high limit switch 164 is physically located above the pressure plate 30 at the top of the compaction compartment 12 and is actuated to an open condition whenever the pressure plate 30 reaches its uppermost or "return" position. Therefore, during operation of the compaction unit, the switch 164 is closed to provide a holding signal (the significance of which will become clear) at a terminal 170 and a d.c. input signal to the pressure switch 160.

A second pressure plate position sensing switch 172, hereinafter called the "low limit" switch, is connected in series with the normally open contact of the pressure switch 160 and operates in conjunction with the switch 160 to provide a positive d.c. voltage of the terminal 174 whenever the contents of the chamber 12 exceed a predetermined full level at the end of the downward motion of the pressure plate 30. Specifically, the switch 172 is closed whenever the pressure plate 30 is above the full level and open when the plate 30 is below the full level. Therefore, a full condition indicating signal is produced at terminal 174 only if the pressure plate 30 encounters the threshold resistance pressure while at a position above the low limit threshold level.

Turning now to FIGS. 2b and 2c, it is seen that the terminals to the left of these FIGS. correspond in number to the terminals to the right of FIG. 2a, and for clarity, are provided with functional designations providing ease of description. The reader is cautioned not to assume that all signals necessarily flow from left to right, since the reverse is often true, particularly in the instance of the hold terminal 170 and the lower six terminals hereinafter described.

It will be recalled that the initiation signals provided at the terminals 150, 152 for the BALE and PACK-RETURN functions are momentary. For the purpose of providing a memory during the respective BALE and PACK-RETURN operations, there is provided a bale memory circuit 180 and a pack memory circuit 182 which are similar, but not identical in operation. The bale memory circuit 180 assumes a first state during the entire bale cycle and a second state at all other times. The pack memory 182 assumes a first state during the entire pack or return cycles and a second state at all other times.

Taking the pack memory 182 first, it is seen that the circuit is principally composed of a silicon controlled rectifier (SCR) 184 having its anode supplied by a hold line 171 connected to the hold terminal 170 and its cathode terminal connected to, among other things, a motor relay drive circuit 186. The gate terminal of the SCR 184 receives its trigger signal from the pack initiation signal at the terminal 152 through an R-C decoupling network 188, a blocking diode 190 and a resistor 192. An additional bias resistor 194 connects the gate and cathode terminals of the SCR 184.

As a brief operational reference, it should be noted that the pack initiation signal at the terminal 152 initially provides anode voltage to the hold line 171 through a directional diode 198, while at the same time providing a trigger signal to the gate terminal of the SCR 184 to initiate conduction therein.

The motor relay driver circuit 186 includes a switching transistor 200 of the NPN type, an emitter dropping

resistor 202 and a base-emitter bias network consisting of resistors 204, 206. The junction of the resistors 204, 206 receives a drive signal from the cathode of the SCR 184. The transistor 200 is referenced to ground potential through the emitter resistor 202 and has its collector connected to one terminal of the motor drive relay solenoid 72 through the connecting terminal 208.

It should be noted at this point that the energization of the motor drive relay solenoid 72 (FIG. 2a) initiates 10 movement of the pressure plate 30 in one direction or the other, depending on the condition of energization of the directional valve solenoid 78. The directional valve is so constructed that it normally routes hydraulic fluid in a direction tending to facilitate upward movement of the pressure plate 30. When energized, the solenoid 78 reverses the flow of hydraulic fluid to facilitate downward movement of the pressure plate 30.

For selectively energizing the directional valve solenoid 78 there is provided a down relay driver circuit 20 212 consisting of a transistor 214 of the NPN type having its emitter referenced to ground through a resistor 216 and its base biased by a network consisting of resistors 218, 220. The collector of the transistor 214 is connected to the control terminal of the directional valve solenoid 78 through a terminal connector 222. When rendered conductive, the transistor 214 is operative to energize the solenoid 78.

The down relay driver circuit 212 is initially rendered 30 conductive by either the bale initiate pulse at terminal 150 or the pack initiate pulse at terminal 152. Specifically, the bale initiate pulse reaches the relay drive through an R-C decoupling circuit 226, a directional diode 228 poled to conduct current toward the transistor 214 and a pair of series resistors 230, 231, the latter of which supplies current to the junction of the resistors 218, 220 to bias the transistor 214 into conduction.

The pack initiation signal at the terminal 152 similarly begins conduction in the driver transistor 214 by providing current to the transistor through a directional diode 236 and the aforementioned network consisting of the series resistors 230, 231 and the bias network consisting of the resistors 218, 220.

The down relay driver circuit 212 and the conduction initiating circuit described thus far merely initiates conduction in the solenoid 78. For the purpose of providing sustaining current for the drive transistor 214, there is provided a drive-down memory circuit 240 consisting of a silicon controlled rectifier 242 having its cathode connected to the bias resistors 218, 220 of the directional solenoid driver circuit 212 and its gate terminal connected to the junction of the bias resistors 230, 231, 394. Anode current for the SCR 242 is normally provided from the power supply 80 through the normally closed (lower position) terminal of the pressure switch 160, the drive-down terminal connector 166 and an R-C decoupling network 244.

While the relay driver circuit 212 is held in conduction by the conducting SCR 242 of the drive down memory circuit 240, a visual indication of downward travel of the pressure plate 30 is provided by an indicator lamp 246 on the front panel 50 (FIG. 1 and FIG. 2a). As in the case of the down direction solenoid 78, sustaining current for the down direction indicating light 246 is primarily provided by the drive down memory circuit 240. To this end, there is additionally provided a down lamp driver circuit 250 which includes a transistor 252 of the NPN type having its emitter cou-

pled to ground through a resistor 254, its collector coupled to the down lamp 246 through a connector terminal 256 and its base terminal connected to the cathode of the SCR 242 through a directional diode 258 in series with an input resistor 260. Quite clearly, the SCR 242, when rendered conductive, simultaneously provides drive current to the down relay driver circuit 212 and the down lamp driver circuit 250 so as to cause energization of the directional solenoid 78 and illumination of the down light 246 respectively. A final function of the drive-down memory circuit 240 is the provision of a signal for inhibiting operation of the up-lamp driver circuit 302 in a manner described more fully below. Since the function of the overall control circuit during the down cycle of the pressure plate 30 is in many respects identical during both the BALE and PACK modes, the operational description of the drive-down function should be prefixed with a description of the bale memory circuit 180.

The bale memory circuit 180 includes a silicon controlled rectifier 266 and a gate terminal bias network consisting of resistors 268, 280. Holding current for the anode terminal of the SCR 266 is normally provided from the power supply 80 through the normally closed (lower) contacts of the pressure switch 160 via the drive-down connector terminal 166 and the R-C decoupling network 244. Current from the cathode of the SCR 266 is coupled through a directional diode 282 to a connection 284 with the cathode terminal of the pack memory SCR 184 from which point the drive current for the motor relay driver circuit 186 is derived. Finally, the gate terminal of the SCR 266 in the bale memory circuit 180 receives its trigger signal in response to the occurrence of a bale initiation pulse at the terminal 150, current being routed to the gate terminal of the SCR 266 through the R-C decoupling network 266, a direction diode 290 and the bias resistor 268.

A brief description of the operation of the circuit described thus far will facilitate further analysis of the system as a whole. Before initiation of either of the principal functions, the system is in a quiescent condition in which the pressure plate 30 is at its uppermost position. The high limit switch 164 is open so that the d.c. supply voltage is not present at terminals 166, 170, 174 in which case the pack memory circuit 182 and the bale memory circuit 180 are inactive or non-conductive. Manual operation of the function selector switch 140 to the PACK-RETURN position causes a pack initiation pulse to be routed from the power supply 80 to the pack connector terminal 152. Anode circuit for the pack memory SCR 184 momentarily flows through the directional diode 198 from the R-C decoupling network 188, while gate current for the same SCR 184 is provided through the diode 190 and resistor 192. The SCR 184 begins conducting and, via its cathode current, renders the motor relay driver circuit 186 conductive to provide a current path to ground for the motor relay solenoid 72 through the connector terminal 208 and the transistor 200. Thus the pump motor begins to run. Simultaneously, current is routed from the pack terminal 152 through the diode 198 to the hold terminal 170 and back through the pressure switch 160 to the drive down terminal 166. The presence of a signal at the terminal 166 provides current for the anode of the drive down memory SCR 242, while the gate terminal of the SCR 242 is being supplied with trigger cur-

rent from the pack terminal 152 through the directional diode 236 and resistor 230. The SCR 242 begins conduction. The gate signal for the SCR 242 is also applied to the down relay driver circuit 212 through the resistor 231 so as to initiate conduction in the transistor 214 to energize the directional valve solenoid 78 so that the pressure plate 30 begins movement in a downward direction.

As the pressure plate 30 leaves its rest position, the high limit switch 164 (FIG. 2a) closes to replace the pack initiation signal as a source of drive current for the hold terminal 170, which supplies the anode of the pack memory SCR 184, and the drive down terminal 166, which supplies the anode current for the drive down memory SCR 242.

The pressure plate 30 continues its downward travel, with the drive-down memory circuit 240 holding the down lamp driver circuit 250 and the down relay driver circuit 212 in conduction.

Initiation of the BALE function by movement of the mode selector switch 140 to the BALE position produces a similar result, since both the bale and pack functions have a common start. The bale initiation pulse at the terminal 150 activates the bale memory circuit 180 by simultaneously providing a signal to the gate of the SCR 266 (through the R-C network 226, the diode 290 and resistor 268) and to the anode thereof (through a diode 292, the hold terminal 170, the pressure switch 160, the drive down terminal 166, and the R-C decoupling network 244). The anode of the drive down memory SCR 242 is connected to the anode of the bale memory SCR 266 and is supplied simultaneously therewith, while the gate voltage for the SCR 242 is supplied from the bale terminal 150 through the R-C network 226, the diode 228 and resistor 230. Conduction through the down relay driver circuit 212 is initiated by the bale initiate pulse appearing at the gate of the drive down memory SCR 242, and conduction in both the down relay driver circuit 212 and the down lamp driver circuit 250 is sustained by conduction through the drive-down memory SCR 242.

In addition to the down direction lamp 246, there is provided an up direction lamp 300 for indicating to the operator the condition of upward travel of the pressure plate 30. The lamp 300 is controlled by an up lamp driver circuit 302 consisting of a transistor 304 of the NPN type having its emitter coupled to ground through a resistor 306 and its collector connected to the control terminal of the lamp 300 through the up lamp drive connector terminal 308. Conduction through the transistor 304, and hence illumination of the up lamp 300, is normally controlled by the conduction state of the pack memory SCR 184 as a result of the connection of the cathode of the SCR 184 to the base of the transistor 304 through a pair of input resistors 310, 312. However, it is desirable to inhibit operation of the up lamp driver transistor 304 and the lamp 300 when the pack memory SCR 184 is in conduction if the pressure plate 30 is moving in the down direction. To this end, there is provided a second transistor 314 of the NPN type which is shunted across the base-emitter circuit of the transistor 304 and controlled from the cathode of the drive memory SCR 242 via a base resistor 316. The emitter of the up lamp driver inhibit transistor 314 is referenced to ground through an emitter resistor 318. Whenever the drive down memory SCR 242 is conducting, the inhibiting transistor 314 is similarly con-

ducting to render the up lamp transistor 304 non-conductive.

At this point it should be noted that movement of the pressure plate 30 in the upward direction is a distinct part of the packing function and occurs automatically as a result of initiation of this function. Upward movement of the pressure plate 30 does not automatically occur as a result of initiation of the baling function. Therefore, it is necessary for the operator to manually engage the mode selector switch 140 and turn it to the PACK-RETURN position at the end of the baling function in order to begin the upward movement of the pressure plate 30.

Returning to the operational description of the packing function, the pressure plate 30 travels down through the chamber 12 and compresses the contents thereof until the predetermined threshold pressure (approximately 2,000lbs. in an actual application) is reached. At this point the contact arm of the pressure switch 160 moves from its normally closed position to an open position (upward in FIG. 2a) which causes supply voltage to be removed from the drive down terminal 166 and hence from the anode of the drive down memory SCR 242. Conduction in the down relay driver circuit 212 and the down lamp driver circuit 250 stops, causing deenergization of the directional valve solenoid 78 and extinguishing the down indicator light 246 on the operator's panel 50. The up lamp driver circuit 302 immediately becomes conductive to illuminate the up direction lamp 300 as the inhibiting transistor 314 is rendered non-conductive along with the drive down memory SCR 242.

Deenergization of the directional valve solenoid 78 allows the directional valve to return to its normal condition which causes the pressure plate 30 to be driven in the upward direction. Since the motor relay driver circuit 186, and the motor drive solenoid 72 are held in conduction by the conductive condition of the pack memory SCR 184, the pressure plate 30 automatically reverts from travel in the downward direction to travel in the upward direction toward a position of full retraction from the contents of the chamber 12. Also, since the pack memory SCR 184 remains in conduction, the up lamp driver circuit 302 remains in conduction to give a visual indication to the operator of the direction of movement of the pressure plate 30.

The pressure plate 30 moves upward through the chamber 12 to the retracted position at which point it comes in contact with the actuator for the high limit switch 164, opening the switch 164 and disconnecting the d.c. power supply from the hold terminal 170, and hence depriving the pack memory SCR 184 of its anode current. As the pack memory SCR 184 ceases conduction, drive current for the motor relay driver 186 disappears and the pump motor drive solenoid 72 is deenergized. The pump stops and the machine remains in a quiet condition until a further operation is initiated. Also, as the pack memory SCR 184 ceases conduction, drive current for the up lamp driver transistor 304 disappears and the up direction lamp 300 is extinguished.

The termination of the BALE function is similar. As the pressure plate 30 moves downward through the chamber 12 to compress the material to be baled, it eventually encounters resistance equal to the threshold pressure of the switch 160, causing the contact arm of the switch 160 to move upward from its normally

closed terminal so as to remove the d.c. supply voltage from the drive down connector terminal 166. During the downward operation of the pressure plate 30 in the BALE mode, the bale memory circuit 180, the motor relay driver 186, the drive-down memory 240, the down-relay driver circuit 212, and the down lamp driver circuit 250 are conductive. However, removal of the d.c. supply voltage from the drive down connector terminal 166 deactivates the bale memory circuit 180 by depriving the SCR 266 of its anode current and simultaneously deactivates the drive-down memory circuit 240 by depriving the SCR 242 of its anode current. Deactivation of the bale memory circuit 180 terminates the drive current to the motor relay driver 186, while deactivation of the drive-down memory circuit 240 terminates the input current to the down relay driver circuit 212 rendering this circuit inoperative so as to leave the pressure plate 30 in its lower position to hold the contents of the chamber 12 at the threshold compression pressure. The door 16 to the chamber 12 may then be opened to allow the operator to tie the compressed bundle.

The function of the down lamp memory circuit 320 is to provide a visual signal to the operator of the position of the pressure plate 30 when the bale cycle is completed. The bale cycle terminates when the compaction chamber 12 contents are subject to the maximum compression pressure of the pressure plate 30. When the machine is in this state, the d.c. supply voltage to the pressure hold down terminal 166 is removed by the opening of the compression pressure switch 160. Thus, the drive down memory SCR 242 is deprived of anode voltage and ceases conduction. At this point, the down lamp driver transistor 252 would also cease to conduct and the down lamp 246 would be extinguished if an alternate source of drive for the down lamp driver transistor 252 was not provided. It is the function of the down lamp memory circuit 320 to provide this alternate drive source, thereby enabling the operator to receive a visual output of the position of the pressure plate 30 while the machine is in the completed bale cycle and idle.

Specifically, the down lamp memory circuit 320 is principally composed of a SCR 322 having its anode terminal supplied by the off terminal 143 through an R-C decoupling network 324 and its cathode terminal connected to the base of the down lamp driving transistor 252 through a resistor 326. The cathode terminal of the SCR 322 is also referenced to ground through a resistor 328. The gate terminal of the SCR 322 receives its trigger signal from the bale initiation terminal 150 through an R-C decoupling network 226, a blocking diode 328 and a bias resistor 330. An additional bias resistor 332 connects the gate and cathode terminals. Thus, the SCR 322 begins conduction whenever its gate terminal receives a bale initiation signal from the manual mode selector switch 140 through the bale initiation terminal 150 and ceases conduction only when its anode terminal current is interrupted by turning the manual mode selector switch 140 to the PACK-RETURN position.

It will be recalled from the prior description that the contacts 141, 142 of the manual mode selector switch 140 are normally closed in the OFF and BALE positions and normally open in the PACK-RETURN position. Thus, the SCR 322 of the down lamp memory circuit 320 and the down lamp driving transistor 252 are

in conduction and the down lamp 246 remains illuminated after maximum compression pressure of the pressure plate 30 is achieved. Only when the operator subsequently generates a pack initiate signal by turning the manual mode selector switch 140 to the PACK-RETURN position are these circuits 320, 250 deenergized and the down lamp 246 extinguished.

The functioning of the return logic circuitry 450 will be discussed below. Suffice it to say at this time that the operator has the capability, after the compressed material has been bound and the compaction chamber doors 16, 28 have been closed thereby activating the magnetically actuated switch 130, to cause retraction of the pressure plate 30 to its uppermost position by turning the manual mode selector switch 140 to the PACK-RETURN position. The compaction chamber door 16 may then be reopened to allow removal of the compressed bundle.

Note that the magnetically actuated switch 130 requires that both compaction chamber doors 16, 28 be closed before any movement of the pressure plate 30 can be initiated or sustained. That is, if the magnetically actuated switch 130 is open, the manual mode selector switch 140 is disabled from sending any pressure plate 30 initiating signals to the bale initiate terminal 150 or the pack initiate terminal 152. Also, if the pressure plate 30 is in motion, opening of either of the compaction chamber door 16, 28 also opens the magnetically actuated switch 130, thereby depriving the hold terminal 170, the pressure plate drive down terminal 166, the pack memory circuit 182, the bale memory circuit 180 and the motor relay drive circuit 186 of supply voltage. Thus any movement of the pressure plate 30 immediately ceases upon opening of either compaction chamber door 16, 28. Therefore, it is possible for the operator to remove the compressed bundle without any interference from or injury caused by movement of the pressure plate 30.

Turning now to the tamping function, it will be recalled that this function occurs whenever the volume of the compaction chamber 12 approaches a predetermined full level. This function generates a second compaction cycle if the first compaction cycle fails to compress the volume of the compaction chamber 12 below the full level. If the second compaction cycle compresses the volume below the full level, additional material may be inserted. However, if the volume remains above the full level after the second compaction cycle, the operator is visually signaled that the compaction chamber 12 is full, indicating that the contents of the chamber 12 should be removed before attempting further compacting. Specifically, the full memory circuit 340, the tamp pulse generator 360, the tamp memory 380, the full lamp memory 400, the full lamp flasher circuit 410 and the full lamp driver circuit 430 accomplish these functions in the manner hereinafter described.

The full memory circuit 340 is principally composed of an SCR 342 having its anode terminal supplied by the d.c. supply line at the terminal 148 through the R-C decoupling network 324 and its cathode terminal connected to the bias resistors 364, 366, 370 of the tamp pulse generator 360. The gate terminal of the SCR 342 is connected to the full condition terminal 174 through the R-C decoupling network 350, the directional diode 344 and the bias resistor 346. An additional bias resistor 348 connects the gate and cathode terminals of the

SCR 342. The SCR 342 begins conduction when a positive pulse at the full condition terminal 174 is conducted through the R-C decoupling network 350, the directional diode 344 and the bias resistor 346 to the gate terminal of the SCR 342. The full condition pulse is generated at the full condition terminal 174 whenever the pressure plate 30 moves from its uppermost rest position, thereby closing the normally open contacts of the high limit switch 164, and reaches the threshold compression pressure of the pressure switch 160 before the pressure plate 30 advances to the predetermined full level of the compaction chamber 12. The low limit switch 172, which is normally closed, is mechanically actuated to an open condition whenever the pressure plate 30 advances to a position below the predetermined full level.

The details of mechanical actuators for level sensing switches, such as the low limit switch 172, are within the knowledge of those skilled in the art and need not be set forth here. Thus, anytime that the machine compacts its contents to the point where the pressure plate 30 is above the full level when the maximum compaction pressure is achieved, a full condition pulse is generated at the full condition terminal 174. When the full condition pulse is applied to the gate terminal of the full memory SCR 342, the SCR 342 begins conduction and supplies operating voltage to the tamp pulse generator circuit 360.

The tamp pulse generator circuit 360 is principally composed of a programmable unijunction transistor (PUT) 362 having its gate terminal connected to the voltage reference resistors 370, 372, with the resistor 370 connected to the cathode terminal of the SCR 342 and the resistor 372 reference to ground. The anode of the PUT 362 is connected to the timing resistor 366 and the timing capacitor 368, with the timing resistor 366 also connected to the cathode terminal of the SCR 342 and the timing capacitor 368 reference to ground. The load resistor 364 provides a sufficient load to the full memory SCR 342 to ensure that the SCR 342 remains in conduction and is connected between the cathode terminal of the SCR 342 and ground. The cathode terminal of the PUT 362 is referenced to ground through the resistor 374 and is connected to the tamp memory SCR 382 through the gate terminal biasing resistors 376, 384.

The function of the tamp pulse generator circuit 360 is to provide a pulse to the tamp memory circuit 380 which is delayed in time with respect to the initiation of conduction in the full memory SCR 342. When the SCR 342 begins conduction, a voltage reference is immediately established on the gate terminal of the PUT 362 by the voltage reference resistors 370, 372. The voltage of the timing capacitor 368 begins to rise as it is charged through the timing resistor 366. When the voltage on the timing capacitor 368, and hence that on the anode terminal of the PUT 362, reaches the voltage reference at the gate terminal of the PUT 362, the PUT 362 is triggered into conduction and the charge on the timing capacitor is discharged through the PUT cathode terminal to generate a positive pulse to the gate biasing resistors 376, 384 of the tamp memory SCR 382. The delay time of the pulse is directly proportional to the value of the timing resistor 366 and the timing capacitor 368, the values being selected to produce a delay time of a few seconds, e.g., 5 seconds.

The tamp memory circuit 380 is principally composed of an SCR 382 having its anode connected to the d.c. supply through the off terminal 148 and the R-C decoupling network 324 and its gate terminal connected to the biasing resistors 376, 384. The cathode terminal of the tamp memory SCR 382 is referenced to ground through the resistor 386 and is also connected to the anode of the full lamp memory SCR 402 and to the differentiating capacitor 388. The other terminal of the differentiating capacitor 388 is referenced to ground through the resistor 390 and is connected to the gate of the drive down memory SCR 242 through the directional diode 392 and the resistor 394.

The function of the tamp memory circuit 380 is to provide d.c. supply voltage to the anode of the full lamp memory SCR 402 and to provide a trigger pulse to the gate of the drive down memory SCR 242. When the SCR 242 is triggered into conduction, the down relay driver circuit 212 and the down lamp circuit 250 are also activated. Thus, the pressure plate 30 which was returning to its uppermost position is caused to change direction and again compress the material in the compaction chamber 12. It should be noted that it is possible to obtain more than one tamping cycle, which this specific application utilizes, by merely adding more tamp pulse generator circuits 360 and tamp memory circuits 380 such that each successive tamp pulse generator circuit 360 is initiated by a prior tamp memory circuit 380.

The full lamp memory circuit 400 is primarily composed of an SCR 402 having its anode terminal connected to the cathode terminal of the tamp memory SCR 382 and its cathode terminal connected to the resistors 414, 418, 422 of the full lamp flasher circuit 410. The gate terminal of the SCR 402 is connected to the full condition terminal 174 through the R-C coupling network 350, the directional diode 404 and the bias resistor 406. An additional bias resistor 408 connects the gate and cathode terminals of the SCR 402.

The function of the full lamp memory circuit 400 is to provide d.c. supply voltage to the full lamp flasher circuit 410 whenever the pressure plate 30 reaches its maximum compaction pressure on the last tamp cycle if the pressure plate 30 is still above the predetermined full level. If, on the last tamp cycle, the maximum compaction pressure occurs before the pressure plate 30 advances below the full level, a full condition pulse is generated at the full condition terminal 174, as previously described. The full condition pulse is applied to the gate terminal of the full lamp memory SCR 402 through the R-C decoupling network 350, the directional diode 404 and the bias resistor 406. Since the anode terminal of the SCR 402 had d.c. supply voltage applied by the conduction of the tamp memory SCR 382, the SCR 402 is now triggered into conduction. Note that if the tamping function is successful in compressing the contents of the compaction chamber 12 to a point below the full level, a full condition pulse is not generated at the full condition terminal 174 at the end of the tamping cycle because the low limit switch 172 opens whenever the pressure plate 30 advances to a point below the full level. Thus, the full lamp memory SCR 402 is triggered into conduction only if the tamping operation is unsuccessful in compacting the material in the compaction chamber 12 to a point below the full level.

The full lamp flasher circuit 410 consists primarily of a programmable unijunction transistor (PUT) 412 having its gate terminal connected to a pair of voltage reference resistors 414, 416 and its anode is connected to a timing resistor 418, a timing capacitor 420 and the full lamp driver resistor 436. The timing resistor 418 is referenced to the d.c. supply voltage provided by the full lamp memory SCR 402 and the timing capacitor 420 is referenced to ground. The load resistor 421 ensures that sufficient load is provided to the full load memory SCR 402 to sustain its conduction. The cathode of the PUT 412 is connected to a discharge resistor 422 which is referenced to ground. When the full lamp memory SCR 402 begins conduction, the voltage reference resistors 414, 416 immediately establish a voltage reference at the gate terminal of the PUT 412. The timing capacitor 420 begins to charge through the timing resistor 418. When the timing capacitor voltage, and hence the voltage at the anode terminal of the PUT 412, reaches the voltage reference established at the gate terminal of the PUT 412, the PUT 412 is triggered into conduction, discharging the timing capacitor 420 through the cathode terminal of the PUT 412 and the resistor 422. The charging and discharging of the timing capacitor 420 continue as long as the full lamp memory SCR 402 provides d.c. supply voltage. Thus, the output to the full lamp driver circuit 430 is a sawtooth waveform and the full lamp flasher circuit 410 functions as a sawtooth oscillator. The period of the sawtooth waveform is dependent upon and directly proportional to the selected values of the timing resistor 418 and the timing capacitor 420, the values being selected to produce a waveform period of less than about 1 second, e.g., about $\frac{1}{2}$ second.

The full lamp circuit consists primarily of a Darlington connection of two transistors 432, 434 of the NPN type with their collector terminals connected to the full lamp 440 through the full lamp terminals 438. The emitter terminal of the transistor 432 is connected to the base terminal of the transistor 434 and the emitter of the transistor 434 is referenced to ground through the resistor 442. The base terminal of the transistor 432 is connected to the timing capacitor 420 and the anode terminal of the PUT 412 through the resistor 436. The sawtooth waveform from the full lamp flasher circuit 410 alternately drives the full lamp driver transistor 432, 434 into and out of conduction. The on and off switching of the full lamp driver transistors 432, 434 causes the full lamp 440 to flash, creating a more noticeable and visible warning indicator to the operator that the contents of the compaction chamber 12 should be removed. The full lamp 440 will continue to flash on and off until the anode terminal voltage of the tamp memory SCR 382 is removed. Specifically, flashing of the full lamp 440 may be extinguished by turning the manual mode selector switch 140 to the PACK-RETURN position which causes the off terminal 148 to drop in voltage.

Directing attention now to the return function, this function is useful for returning the pressure plate 30 to its uppermost position after the baling operation or after any machine malfunction or other occurrence leaves the pressure plate 30 in any position except its uppermost position. One example of an occurrence which leaves the pressure plate 30 in a lowered position is the opening of either compaction chamber door 16, 28 while the pressure plate 30 is in motion. This causes

the magnetically actuated switch 130 to open whereupon movement of the pressure plate 30 immediately ceases.

It will be recalled that whenever the pressure plate 30 is not in its uppermost position, the low limit switch 164 is closed maintaining the hold terminal 170 at the d.c. supply voltage. The return circuit 450 receives d.c. supply voltage from the hold terminal 170 through the directional diode 454. The capacitor 464 which is referenced to ground is connected to the d.c. supply voltage through the resistor 460. The pulse generating PUT 474 has its anode terminal connected to a capacitor 472 which is referenced to ground, a pair of voltage reference resistors 468, 470 and the directional diode 466. The gate terminal of the PUT 474 is connected to a resistor 476 which is referenced to the d.c. supply voltage at the capacitor 464. The cathode terminal of the PUT 474 is connected to the gate biasing resistors 478, 480 of the return memory SCR 482. An additional SCR 482 gate to cathode terminal bias resistor 484 is used. The anode terminal of the SCR 482 is connected to the hold terminal 170 through the line smoothing capacitor 492 and the directional diode 454. The cathode terminal of the SCR 482 is referenced to ground through the resistor 486 and is connected to the base terminal of the return current driving transistor 409 of the NPN type through the resistor 488. The emitter terminal of the transistor 409 is connected to ground while its collector terminal is connected to the anode terminal of the bale memory SCR 266 and the anode terminal of the drive down memory SCR 242. The return logic generation transistor 462 of the NPN type has its base terminal connected to the pack initiate terminal 152 through the directional diode 452 and the resistor 456 and is referenced to ground through the resistor 458. The emitter terminal of the transistor 462 is connected to ground while its collector terminal is connected to the capacitor 464 and the resistors 460, 470, 476.

The return circuit 450 functions to deenergize the bale memory circuit 180 and the drive down memory circuit 240 in the manner hereinafter described. The return circuit 450 receives d.c. supply voltage from the hold terminal 170 through the directional diode 454. The capacitor 464 rapidly charges toward the d.c. supply voltage through the resistor 460. The capacitor 472 charges rapidly toward the voltage reference level determined by the voltage reference resistors 468, 470. When the operator wishes to return the pressure plate 30 toward its uppermost position, the manual mode selector switch 140 is turned to the PACK-RETURN position. A pack initiate pulse is then generated at the pack initiate terminal 152 which is conducted to the base of the return logic transistor 462 through the R-C decoupling network 188, the directional diode 452 and the resistor 456. The pack initiate signal at the base terminal of the transistor 462 causes the transistor 462 to conduct; the collector terminal dropping in voltage to nearly ground potential. The capacitor 464 is rapidly discharged through the transistor 462 and the gate terminal of the return pulse generator PUT 474 is pulled toward ground potential through the resistor 476. The anode terminal of the PUT 474 momentarily stays at the potential of the capacitor 472. As the potential of the gate terminal of the PUT 474 is pulled down by the collector terminal of the return logic transistor 452, the anode terminal of the PUT 474, which has its potential

supported by the capacitor 472, is at a higher potential than the gate terminal. The PUT 474 is triggered into conduction and the capacitor 472 is discharged through the cathode terminal of the PUT 474 and the resistor 478.

The discharging through the resistor 478 generates a positive pulse to the gate terminal of the return memory SCR 482 through the gate bias resistors 480, 484. Since the anode terminal of the return memory SCR 10 482 is connected to the d.c. supply voltage on the hold terminal 170 through the directional diode 454, the SCR 482 is triggered into conduction when the positive pulse is applied to its gate terminal. The conduction of SCR 482 drives the return driving transistor 490 into 15 conduction by supplying base terminal current through the bias resistor 488. The conduction of transistor 490 pulls the pressure plate drive down line, which is connected to the anode terminals of the bale memory SCR 266 and the drive down memory SCR 242, down to ground potential. The SCR 266 and the SCR 242 are now deprived of anode voltage and any prior conduction ceases. Thus, the return logic circuit 450 cancels any prior bale memory 180 and cancels any prior drive down memory 240. The directional valve solenoid 72 20 is deenergized when the drive down memory 240 is cancelled and the directional valve 74 returns to its normal position. Note that when the return logic circuit 450 was actuated by a pulse on the pack initiate terminal 152 and the d.c. supply voltage on the hold terminal 170, the pack memory SCR 184 was triggered into conduction by the presence of the d.c. supply voltage from the hold terminal 170 on its anode terminal and the pack initiate pulse from the pack initiate terminal 152 25 on its gate terminal. Thus, the motor drive relay 172 is energized by the pack memory SCR 184 supplying d.c. voltage to the motor relay driver circuit 186. With the hydraulic solenoid 74 in its normal position and the hydraulic motor 68 running, the pressure plate 30 retracts toward its uppermost position. When the pressure plate 30 reaches its uppermost position, or when refuse is lodged between the compaction chamber top plate 11 and the pressure plate 30, the high limit switch 164 assumes its normally open position causing the d.c. supply voltage on the hold terminal 170 to drop. When refuse is so lodged in the space above the pressure plate 30, the plate 30 upon stopping does not return to its uppermost position, but resumes its next downward stroke from this starting position. Since bias and drive current for the return logic circuit 450 is supplied by the hold terminal 170, the return pulse generator PUT 474, the return memory SCR 482 and the return driver transistor 490 are disabled. The directional diode 466 30 now allows rapid discharge of the capacitor 472 to prevent further PACK-RETURN commands from the operator from generating another return signal.

It will be understood from the above circuit description that if the capacitor 472 was not fully discharged, another return pulse would be generated by the PUT 474 whenever the manual mode selector switch 140 is turned to the PACK-RETURN or BALE positions thereby supplying voltage to the hold terminal 170 through the directional diodes 198, 292. This would result in the undesirable system operation of inhibiting any downward movement of the pressure plate 30. The directional diode 466 provides a rapid discharge path for the capacitor 472 and eliminates this problem. If the capacitor 472 is discharged, no such hazard occurs

since the gate terminal of the PUT 474 rises to a higher potential and at a faster rate than the anode terminal when the manual mode selector switch 140 initiates the PACK-RETURN or BALE functions as described above.

Turning now to the automatic shut-off function, this function deenergizes the drive motor after a predetermined short period of time, e.g. 45 seconds, beyond the initiation of any operation by the operator. This function prevents damage to the unit or injury to the operator which might result from any system malfunction.

The automatic shut-off function is performed by the end cycle timer circuit 500. The d.c. supply voltage for the end timer circuit 500 is derived directly from the pressure plate drive down terminal 166. The end cycle PUT 502 has its gate terminal connected to a pair of voltage reference resistors 508, 510 and its anode terminal connected to a timing resistor 504 referenced to the d.c. supply voltage and a timing capacitor 506 referenced to ground. The timing capacitor 506 charges through the timing resistor 504 until the anode terminal potential of the PUT 502 reaches the potential of the gate terminal. The PUT 502 is then triggered into conduction and the timing capacitor 506 is discharged through the PUT 502 cathode terminal and the resistor 512 which is referenced to ground. The delay time of the pulse which is generated at the resistor 512 is directly proportional to the selected values of the timing resistor 504 and the timing capacitor 506, the values being selected to produce a short delay time, e.g. of about 45 seconds. The delay pulse generated at the resistor 512 drives a pair of transistors 514 and 516 of the NPN type and connected in the Darlington configuration. The base terminal of the transistor 514 is connected to the discharge resistor 512 and the PUT 502 cathode terminal and the emitter terminal of the transistor 514 is connected to the base terminal of the transistor 516. The transistor 516 has its emitter connected to ground. The collectors of both transistors 514, 516 are connected directly to the pressure plate drive down terminal 166.

When the pressure plate 30 leaves its uppermost position, the high limit switch 172 closes and d.c. supply voltage is provided to the end cycle timer circuit 500 through the compression pressure switch 160 and the pressure plate drive down terminal 166. If the pressure plate 30 fails to reach maximum compression pressure within 45 seconds, in this example, thereby opening the compression pressure switch 160, the PUT 502 is triggered into conduction as previously described. The delay pulse from the PUT 502 cathode terminal drives the end cycle driver transistors 514, 516 into conduction which causes the d.c. supply voltage on the pressure plate drive down terminal 166 to drop. Since the hold terminal 170 is connected to the pressure plate drive down terminal 166 through the compression pressure switch 160, the d.c. voltage level of the hold terminal 170 drops with that of the pressure plate drive down terminal 166. The drop in voltage on both of these terminals causes the anode terminals of the pack memory SCR 184 and the bale memory SCR 266 to cease any prior conduction. Since the motor relay driver circuit 186, which energizes the motor relay 72, receives its d.c. supply voltage from either of the SCR's 184, 266, the motor relay circuit 186 and the motor relay 72 are deenergized. Thus, the drive motor 68 is deactivated and the pressure plate 30 ceases any motion. After the

malfunction is repaired, the pressure plate 30 can be retracted to its uppermost position by using the previously described return function.

If the pressure plate 30 reaches maximum compression pressure within the exemplary 45 second delay of the end cycle timer circuit 500, the circuit 500 is reset to begin another 45 second delay period when the pressure plate 30 begins retracting toward its uppermost position. The interruption of the d.c. supply voltage on the pressure plate drive down terminal 166 by the compression pressure switch 160 causes the gate terminal of the PUT 502 to drop in voltage along with the pressure plate drive down terminal. However, the voltage of the anode terminal of the PUT 502 is supported by the timing capacitor 506. As the voltage of the gate terminal of the PUT 502 drops below that of the anode terminal, the PUT 502 is triggered into conduction and the timing capacitor 506 is discharged through the cathode terminal of the PUT 502, the discharge resistor 512 and the drive down transistors 514, 516. Thus, the end cycle timer circuit 500 is reset to begin another delay period to deenergize the motor drive relay in the event that some malfunction prevents the pressure plate 30 from reaching its uppermost position within 45 seconds.

Note that the pressure plate 30 retraction is automatic when the system is in the compaction mode and must be manually initiated by the manual mode selector switch 140 when the system is in the bale mode. However, the delay period does not begin until the system is manually initiated (assuming no leakage of hydraulic fluid and consequent loss of fluid pressure due to leaky seals and the like) when it is in the bale mode because of the opening of the compression pressure switch 160 when maximum compression pressure is achieved deprives the end cycle timer circuit 500 of d.c. supply voltage.

Similarly, when the system is in the tamp mode, each achievement of maximum compression pressure of the pressure plate 30 opens the pressure switch 160 and interrupts the d.c. supply voltage to the end cycle timer circuit 500. The circuit 500 is thereby reset to begin another delay period for each change in direction of the pressure plate 30. The end cycle timer circuit 500 has no effect on normal compaction cycles since normal movement of the pressure plate 30 in any direction ceases within the delay period.

The above discussion has described the five principal functions of the system: the compact function, the bale function, the tamp function, the return function and the automatic shut-off function. The accessory relay driver circuit 520 illustrates the capability of adding additional control functions to the system. This circuit 520 is presented for illustrative purposes only and to indicate the versatility of the control system in allowing additional user-desired functions to be implemented. Such user-desired functions may include, but are not limited to, automatic cycling devices to initiate compaction cycles at predetermined time intervals.

I claim as my invention:

1. A control system for a compacting machine having a compaction chamber for receiving material to be compacted, a pressure plate spanning the area of said chamber for compressing the contents thereof, a reversible drive source for moving said pressure plate in the forward and reverse directions within said compaction chamber, sensing means associated with said drive

source for providing an output whenever the compression pressure of the pressure plate against the chamber contents reaches a predetermined threshold value, means responsive to said output and operative on said drive source to stop the forward advancement of said pressure plate and to hold the contents of said chamber at said predetermined threshold compression pressure to facilitate baling of the compressed contents, and means for reversing the operation of said drive source to retract the pressure plate and permit removal of the compressed contents from the compaction chamber, said control system including means for initiating the forward operation of said drive source, emergency shut-off means including a) time delay means responsive to the initiation of said forward operation for producing an output at a predetermined interval after said initiation of forward operation, and b) means responsive to said output for inhibiting further operation of said drive source, said time delay interval being sufficiently long to enable normal forward or reverse operation of said pressure plate to be completed before said output is produced and sufficiently long to enable normal forward or reverse operation of said pressure plate to be completed before said output is produced and sufficiently short to allow said output to be produced as soon as the period of operation of said drive source exceeds the time normally required for full forward or reverse travel of said pressure plate.

2. A control system for a compacting machine having a compaction chamber for receiving material to be compacted, a pressure plate spanning the area of said chamber for compressing the contents thereof, a reversible drive source for moving said pressure plate in the forward and reverse directions within said compaction chamber, and a panel at the top of the compaction chamber for enclosing said chamber, said control system including means for sensing the fully retracted position of said pressure plate to prevent further retrac-

tion thereof by rendering said drive source inoperative whenever the pressure plate reaches said fully retracted position, and said sensing means also being responsive to the position of the compaction chamber panel to render said drive source inoperative whenever material lodged between the pressure plate and the compaction chamber panel causes said panel to flex as the pressure plate retracts thereby preventing damage to said compaction chamber panel by the retracting pressure plate.

10 3. A control system according to claim 2 wherein the retraction position sensing means comprise a slidably mounted rod projecting through the compaction chamber panel, said rod being engageable by the retracted pressure plate to slidably move upwardly and thereby render said drive inoperative.

4. A control system for a compacting machine having a compaction chamber for receiving material to be compacted, a pressure plate spanning the area of said chamber for compressing the contents thereof, a reversible drive source for moving said pressure plate in

20 the forward and reverse directions within said compaction chamber, a panel at the top of the compaction chamber for enclosing said chamber, retraction position sensing means comprising a slidably mounted rod projecting through the compaction chamber panel, said rod being engageable by the retracted pressure plate to slidably move upwardly and thereby render said drive inoperative, said retraction position sensing means fur-

25 ther including a second retraction position sensing means mounted on said rod and in engagement with the compaction chamber panel so that material lodged between the top of said pressure plate and said panel causes said panel to flex upwardly during retraction of said pressure plate thereby causing upward movement 30 of both the second retraction position sensing means and the rod to render the drive source inoperative and thereby inhibit further retraction of said pressure plate.
